UNITED STATES PATENT OFFICE.

FREDERICK S. McCULLOUGH, OF CLEVELAND, OHIO, ASSIGNOR TO GLENN L. MARTIN,
OF CLEVELAND, OHIO.

RELAY FOR WIRELESS SIGNALING SYSTEMS.

1,403,701.

Specification of Letters Patent. Patented Jan. 17, 1922.

Original application filed January 22, 1917, Serial No. 143,560. Divided and this application filed September 11, 1919. Serial No. 323,065.

To all whom it may concern:

Be it known that I, FREDERICK S. McCULLOUGH, a citizen of the United States, resident of Cleveland, county of Cuyahoga, and 5 State of Ohio, have invented new and useful Improvements in Relays for Wireless Signaling Systems, of which the following is a specification, the principle of the invention being herein explained and the 10 best mode in which I have contemplated applying that principle, so as to distinguish it from other inventions.

This invention relates to relays for wireless signaling systems, and is herein shown 15 and described as embodied in a system for signaling elevators and embodies subject-matter divided out of original application Serial No. 143,560, filed January 22, 1917. An essential object is to provide a simple, 20 efficient means for actuating signals in elevator cars and on the various floors of the building, and which shall be comparatively cheap to manufacture and not liable to get out of order.

25 In the system disclosed in said patent I use a high frequency generator preferably connected by a single wire with capacity members arranged at the several floors for one elevator car or a plurality of elevators 30 in a bank. I arrange capacity members on the car adapted to be brought into proximity with the successive capacity members for the floors so that when a signal switch is actuated on any floor it may connect the corresponding capacity member with the generating means and cause energy to be transmitted across the air dielectric from one capacity to the other while they are adjacent, and I arrange on the elevator car a relay 35 40 adapted to be actuated by the electric impulse passing from one capacity to the other. This relay may control a visual or audible signal on the elevator car.

To make the system more complete I may 45 arrange an additional capacity plate on each car at each floor and a relay on each floor to actuate a signal indicating that a car is about to respond to the signal of the waiting passenger.

50 My invention is hereinafter more fully described in connection with the drawings, which illustrate a convenient arrangement thereof, and the essential characteristics of the invention are set forth in the claims.

Figure 1 is a side elevation of the relay; 55
Figure 2 is an axial section thereof;

Figure 3 is a transverse horizontal section taken substantially on the line 3—3 of Figure 2;

Figure 4 is a similar section taken substantially on the line 4—4 of Figure 2. 60

Figure 5 is a section on the line 5—5 of Figure 2.

For actuation of the signals on the car and on the various floors I provide relays 65 such as disclosed herein which are so constructed as to be actuated by that form of energy which surrounds a wire connected with one terminal of a high potential transformer connected with a high frequency 70 generator and which energy does not depend for its existence upon any return or ground wires. I have found in actual practice that such a relay can be actuated through a single wire so connected even 75 when the wire is divided by capacity plates separated by an air gap of several inches. Thus by bringing such capacities together I accomplish the selective signaling described. One form of such a relay is illustrated in Figures 1 to 5 inclusive and may be constructed as follows: 80

At 70 is indicated a suitable support on which is mounted a block or casing 71 preferably of insulating material. Two lateral 85 extensions 72 and 73 of this casing are connected by a cylindrical member 75 which encloses a substantially cylindrical space communicating with axial bores of the extensions 72 and 73. Within this space is 90 mounted a cylindrical cage 76 carrying transverse leaves 77 somewhat spirally arranged, as indicated, and comprising light thin sheets of metal. At 78 are indicated co-acting wings adapted to be interposed between the leaves 77 and carried on a revolvable and vertically movable spindle 80 shown as supported by a spring 81 at its upper end 95 adjustably carried by a screw 82, threaded through a sleeve 83 to which it may be 100 locked by a nut 84. The sleeve 83 is externally threaded and emphasized by a nut 85 which may provide a binding post for the wire leading to the relay and corresponding to the wire 19. 105

The spindle 80 is provided with a downward extension 86 insulated therefrom and adapted to contact with a plate 87 con-

nected with a battery 88 which is included in one of the signal light circuits, the connection being made through a wire 89 which is so coiled about the extension 86 as not to interfere with its rotation or vertical movement. A suitable cap 90 supports the plate 87 and protects the contact 86.

This relay depends for its operation upon the attraction of one air electrode to another 10 when charged with the energy which follows a wire connected with a source of high frequency current of a high potential. When the field of energy surrounds the wire leading to the relay, the wings 78 are caused 15 to move downwardly and turn slightly within the cage 76 by their attraction to the leaves 77. This action occurs when the capacity plates are in proximity and after the energizing of one of the push button signal 20 circuits which causes the relay to make a contact at 86 and 87, whereupon the light 10^a becomes incandescent.

I found by experiment that this relay may be constructed in many different ways, the 25 essential features being an electrode attracted to some other object, and I have also found that the action may be augmented by the use of a small resistance wire which heats when the energy passes along the 30 same. Accordingly I may make the coil spring 81 of such wire so that its expansion, due to the heating, may increase and make more positive the movement of the relay contact.

35 What I claim is:

1. In a signaling system, an electrostatic relay comprising stationary plates, and movable plates attached to a spindle, said stationary plates and movable plates both 40 being set at an angle less than ninety degrees with said spindle.

2. In a signaling system, an electrostatic relay having, in combination, a movable spindle, vanes attached to said spindle, and 45 a wire supporting said spindle, said wire

being expandible by the heat due to the electric energy conveyed to the relay.

3. In a signaling system, a static relay having, in combination, fixed plates, a movable spindle, vanes attached to said spindle and coacting with said fixed plates, and a wire spring supporting said spindle and adapted to be heated by the electric energy conveyed to the relay.

4. In a signaling system, a static relay 55 having, in combination, fixed plates, a movable spindle, vanes attached to said spindle, said plates and vanes being set so as to make an angle less than ninety degrees with said spindle, and a wire supporting said spindle 60 and adapted to expand when electric energy is conveyed by it.

5. In a signaling system, a static relay having, in combination, fixed plates, a movable spindle, vanes attached to said spindle, said plates and said vanes being set at angles less than ninety degrees with said spindle, a spring supporting said spindle, and a contact member attached to said spindle.

6. In a signaling system, a relay having, 70 in combination, stationary plates, a movable spindle, vanes attached to said spindle, said plates and said vanes being set at an angle with said spindle, so that when they are attracted by each other, said spindle will be 75 caused to rotate and to move longitudinally.

7. In a signaling system, a relay having, in combination, stationary plates, a movable spindle, vanes attached to said spindle, said plates and said vanes being set at an angle 80 other than ninety degrees with said spindle, a conducting support for said spindle adapted to expand when conveying electric energy, said plates and vanes and said conducting support coacting to move said spindle longitudinally.

Signed by me, this 8th day of September, 1919.

FREDERICK S. McCULLOUGH.
